DESIGN FOR A JUVENILE VEHICLE BODY

Herman L. Kraeft, Cleveland Heights, Ohio, assignor to The Murray-Ohio Manufacturing Company, Cleveland, Ohio, a corporation of Ohio

Application November 10, 1938, Serial No. 81,528

Term of patent 7 years

To all whom it may concern:

Be it known that I, Herman L. Kraeft, a citizen of the United States of America, residing at Cleveland Heights, in the county of Cuyahoga and State of Ohio, have invented a new, original, and ornamental Design for a Juvenile Vehicle Body, of which the following is a specification, reference being had to the accompanying drawing, forming a part thereof.

In the drawing, Fig. 1 is a perspective view of the vehicle body; Fig. 2 is a plan view of the vehicle body and Fig. 3 is a side elevational view of the vehicle body.

I claim:

The ornamental design for a juvenile vehicle body, substantially as shown.

HERMAN L. KRAEFT.
